UNITED STATES PATENT OFFICE

2,596,557

SPRING ACTUATED DISK PROJECTOR

Martin Huber, Munich, Germany

Application December 29, 1950, Serial No. 203,279
In Germany January 2, 1950

1 Claim. (Cl. 124—7)

2

My invention relates to games and particularly to a device for shooting or sliding a disc simulating a disc such as is used on a shuffle board or a stone such as is used in curling.

The principal object of my device is to provide a disc shooting apparatus of simple character which is adapted to be clamped to a table top, board or the like, along which the discs are to be slid, and by means of which said discs may be shot at a desirable velocity and aimed as desired.

I accomplish these and other objects by means of the novel elements and the combinations and arrangements thereof described below and illustrated in the accompanying drawing in which—

Fig. 1 is a plan view of my device with the throwing lever pulled back into a position from which it may be released to shoot the disc;

Fig. 2 is a front elevation view of the device with the throwing lever vertical;

Fig. 3 is an elevation view of the device as it may be applied to a figure simulating a human being;

Figs. 4 and 5 are sections of Fig. 2 in the plane 4—4 showing the disc holding means in closed and open position, respectively; and

Fig. 6 is a sectional view of a modification.

Referring to the drawing—

My device comprises a base member 1 which is adapted to be secured to a smooth board or table top 2 by means of a clamp 3. Pivotally secured at 4 to the base 1 is a movable element 5 having an arm 6 by means of which it may be swung about the axis of its pivotal connection to the base plate. The element 5 carries the upright element 7. Secured to the element 7 adjacent the top thereof, is a bearing 8 having a horizontal axis on which the pendulous lever 9 is mounted to swing. An element 10 is secured to the axis of the lever 9 and a tension spring 11 is stretched between a pin 12 at the bottom of the element 10 and a pin 13 secured to the vertical stand 7 near the bottom thereof. The spring 11 is normally under some tension and normally holds the pendulous lever 9 in a vertical position, as shown in Fig. 2.

The preferred form of disc is shown at 14 in Figs. 1—5, inclusive, and is provided with an upright handle 15. Pivotally secured at 16 to the lever 9 near the bottom thereof is a movable jaw or gripping member 17 having an arcuate recess 18 therein adapted to embrace the handle 15 of the disc and hold it against the side of the lever 9 forming a fixed jaw, as best shown in Fig. 4. The movable jaw is normally held in the posi-

tion shown in Fig. 4 by means of a spring 19 which is secured to the lever 9 at 20 and also at the pin 21 intermediate its ends. The free end of the spring 19 extends through a hole in the movable jaw 17, as best shown in Figs. 1, 2, 4 and 5.

In Fig. 3, the upright element 7 has been given the form of a man, as shown at 22, having an arm 23, which is analogous to the lever 9, and which is pivotally connected to the form of the man at 24. The arm 23 functions exactly like the lever 9 and has a spring 19 secured thereto identical with the spring 19, shown in Figs. 1 and 2. A movable jaw 25, in all respects similar to the movable jaw 17, is pivotally secured at 26 to the bottom of the arm 23, and there is an extension 27 at the lower end of the arm, forming a fixed jaw, which cooperates with a depending portion 28 of the movable jaw (see also Figs. 1 and 2) to grip the handle 15 of the disc therebetween. Instead of using a tension spring, such as shown at 11 in Figs. 1 and 2, in the embodiment shown in Fig. 3, a torsion spring 29 is used (see Fig. 6). One end of the torsion spring is connected to the arm 23 by means of a pin 30 and the other end thereof is connected to a pin 31 affixed to the body of the man 22. This spring is not normally under stress when the arm 23 is vertical but when the arm 23 is pulled back into the position shown in Fig. 3, the spring 29 is wound up so that, when the arm is released the spring 29 imparts a quick swinging movement to the arm 23 in a counter-clockwise direction. The spring 11, shown in Figs. 1 and 2, functions in the same way. That is to say, when the lever 9 is pulled into the position shown in Fig. 1, the spring 11 is stretched, and when the lever 9 is released it imparts thereto a quick swinging movement in a counter-clockwise direction, as viewed from the right hand side of either Fig. 1 or Fig. 2. Each spring functions as a brake or damper on the movements of the lever or arm to which it is attached and brings it back to its normal vertical position after a few oscillations.

In operation, the lever 9 or the arm 23 is pulled back by the player into the position shown in Fig. 1 or 3. The handle 15 of the disc is then inserted in the jaws, the direction in which the disc is to be shot is adjusted by means of the handle 6 and the lever 9 or the arm 23, as the case may be, is released. When the lever or the arm reaches an approximately vertical position, the movable jaw 17 strikes the stop 32 which causes the movable jaw to swing about its pivotal connection 16 into the open position shown in Fig. 5 and to release

the disc 14. The force with which the disc is shot may be varied, as desired, by varying the distance which the lever or arm is pulled back before it is released.

While I have described my invention in its preferred embodiment, it is to be understood that the words which I have used are words of description rather than of limitation and that changes, within the purview of the appended claim, may be made without departing from the true scope and spirit of my invention in its broader aspects.

What I claim is:

A game device for shooting a disc simulating a curling stone and having an upstanding handle thereon; said device comprising a base; an upright element, means pivotally securing said element to said base to move about a vertical axis; a lever, means pivotally connecting said lever to said upright element to swing about a horizontal axis, a spring cooperating with said lever and normally but yieldingly holding said lever substantially vertical and adapted to impart a quick swinging movement to said lever

when said lever is pulled out of its normal vertical position and then released, disc-holding means carried by said lever at the lower end thereof comprising a pair of jaws adapted to embrace said handle throughout a substantial portion of the length thereof with said handle substantially vertical when said lever is in its normally vertical position, and means cooperating with at least one of said jaws for automatically releasing said disc when said lever reaches a predetermined point during the swinging movement thereof.
